(57) **CLAIM**

The ornamental design for a retractable blind for covering a raked window as shown and described.

DESCRIPTION

FIG. 1 is an isometric view from below one side and one end of the retractable blind of the invention;

FIG. 2 is an isometric view from above the other side and other end of the retractable blind illustrated in FIG. 1;

FIG. 3 is a side view of the retractable blind of FIGS. 1-2;

FIG. 4 is a view of the other side of the retractable blind of FIGS. 1-3;

FIG. 5 is an end view of the retractable blind of FIGS. 1-4;

FIG. 6 is a view of the other end of the retractable blind of FIGS. 1-5;

FIG. 7 is a top view of the retractable blind of FIGS. 1-6; and,

FIG. 8 is a bottom view of the retractable blind of FIGS. 1-7. The broken lines in the drawings illustrate portions of the article that are not claimed and form no part of the claimed design.
